US0D1071965S

(12) **United States Design Patent** (10) **Patent No.:** **US D1,071,965 S**
Balcerzak (45) **Date of Patent:** **** Apr. 22, 2025**

(54) **DISPLAY SCREEN OR PORTION THEREOF WITH GRAPHICAL USER INTERFACE**

(71) Applicant: **Proxwell LLC**, Philadelphia, PA (US)

(72) Inventor: **Michal Balcerzak**, Philadelphia, PA (US)

(73) Assignee: **Proxwell LLC**, Philadelphia, PA (US)

(**) Term: **15 Years**

(21) Appl. No.: **29/901,982**

(22) Filed: **Sep. 7, 2023**

(51) **LOC (15) Cl.** **14-04**

(52) **U.S. Cl.**

USPC **D14/485**

(58) **Field of Classification Search**

(57) **CLAIM**

The ornamental design for display screen or portion thereof with graphical user interface as shown and described.

DESCRIPTION

FIG. 1 is a front view of a display screen or portion thereof with graphical user interface showing the claimed design; and,

FIG. 2 is a second embodiment thereof.

The outermost broken lines in FIG. 1 and FIG. 2 show a display screen or portion thereof, and form no part of the claimed design. The other broken lines in FIG. 1 and FIG. 2 show portions of the graphical user interface that form no part of the claimed design.

1 Claim, 2 Drawing Sheets
